UNITED STATES PATENT OFFICE.

MASON GILBERT CARPENTER, OF MARIETTA, OHIO.

DRILLING MACHINE.

Application filed December 29, 1924. Serial No. 758,749.

To all whom it may concern:

Be it known that I, MASON GILBERT CARPENTER, a citizen of the United States, residing at Marietta, in the county of Washington, 5 ton and State of Ohio, have invented a new and useful Drilling Machine, of which the following is a specification.

This invention aims to provide, in a machine of the sort above mentioned, a novel 10 drive for the cable spool and the cable wheel, to provide a pumping mechanism of novel form, to improve the construction and operation of the sand line reel, to improve the spudding mechanism, and, generally, to improve 15 and enhance the utility of devices of that sort to which the invention appertains.

Although a preferred form has been shown, it will be understood that a mechanic, working within the scope of what is claimed, 20 may make such alterations as his skill may suggest, without departing from the spirit of the invention.

In the accompanying drawings:—

Figure 1 shows in side elevation, a device 25 constructed in accordance with the invention, the parts being in the positions which they will assume when the spudding operation is being carried out;

Figure 2 is a top plan wherein parts are 30 broken away;

Figure 3 is a longitudinal section wherein parts are omitted;

Figure 4 is a side elevation wherein the walking beam is shown coupled up with its 35 driving mechanism, parts being broken away; and

Figure 5 is a sectional detail, showing in elevation, a portion of the pumping mechanism.

The device forming the subject matter of 40 this application comprises a wheel-mounted frame 1 provided at its forward end with a standard 2 to which a mast 3 is pivoted at 4, so that the mast can be folded back- 45 wardly into an out of the way position, if desired, although a foldable mast is not insisted upon. The lower end of the mast 3 is connected to the standard 2 by a securing member 5, and the mast is sustained 50 by guys 6. The mast 3 carries an upper pulley 7 and a lower pulley 8.

An engine 9 is mounted on the end of the frame 1, and may be of any desired construction. The engine 9 drives a shaft 10 55 journaled on the frame 1 and disposed transversely of the frame, the shaft 10 carrying

a pulley 11 about which is engaged a belt 12 cooperating with a larger pulley 14 on a shaft 15 disposed transversely of the frame 1 and journaled thereon. The shafts 10 60 and 15 may be connected at their outer ends by a brace 16.

The shaft 15 carries a friction wheel 17, located inside the frame 1, the friction wheel 17 being adapted to cooperate with a 65 friction wheel 18 on a shaft 19 carrying the sand line reel 20, one end of the shaft 19 being journaled in a bearing 21 on one side of the frame 1, and the other end of the shaft being journaled shiftably in a bearing 70 22 on the opposite side of the frame, the frame carrying a brake 23, and it being possible to shift the friction wheel 18 into and out of engagement with the friction wheel 17, and into and out of engagement 75 with the brake 23. The mechanism for shifting the shaft 19 in the bearing 22 to cause the friction wheel 18 to cooperate with the friction wheel 17 or with the brake 23, embodies an operating member in the form of a rod 80 24, slidable in a support 25 on the forward end of the frame 1. The sand line, proceeding from the reel 20, over the pulley 8, is marked by the numeral 26.

A shaft 27 extends transversely of the 85 frame 1, the shaft being journaled in a bearing 28 on one side of the frame, and being shiftably journaled in a bearing 29 on the opposite side of the frame, the shaft 27 carrying a friction wheel 30, located within 90 the frame 1, and adapted to be brought into contact with the friction wheel 17, or into contact with a brake 31 on the frame 1. The means for imparting movement to the shaft 27, thereby, to cause the friction 95 wheel 30 to cooperate either with the brake 31 or with the friction wheel 17, comprises an operating member 32, in the form of a rod, extended to the forward end of the frame 1 and slidably supported on the 100 frame.

A shaft 33 is journaled on the frame 1, below and slightly in advance of the shaft 27, the shaft 33 carrying a gear wheel 34. A pinion 35 is splined to the shaft 27, to 105 slide therealong, and, through the instrumentality of the lever 36, extended to the forward end of the frame 1, and fulcrumed intermediate its ends thereof, as shown at 37, the pinion 35 may be shifted into and 110 out of mesh with the gear wheel 34. About shaft 33 is wound a casing line 38 which is

extended over the lower pulley 8 on the mast 3.

The pinion 35 on the shaft 27 may be shifted into and out of mesh with a gear wheel 39 on a shaft 40 journaled on the frame 1, the gear wheel 39 and an end plate 41 forming a reel for the drilling line 42. One end of the shaft 40 carries a disk 43 coacting with a brake strap 44 connected to 10 an arm 45 on a shaft 46 mounted to rock in one side of the frame 1, the shaft 46 having a depending arm 47 connected by a link 48 with an arm 49 on a shaft 50 mounted to rock in one side of the frame, the shaft 50 15 being provided with a forwardly extended handle 51 which is accessible from the forward end of the frame 1.

On the shaft 15 there is an eccentric 52 cooperating with a strap 53 a pitman 54 pivoted to a radius arm 55 mounted to swing on the frame, the radius arm 55 being connected by a link 56 to the plunger 57 of a pump 58 carried by the frame of the machine and communicating with a conduit 59. The pump may be used for any purpose for which a pump is needed.

The line 42 is extended backwardly about an idler 60 on the frame, the idler being located on the rear end of the frame, at a point near to the longitudinal center of the frame. From the idler 60, the line 42 extends outwardly and forwardly about a pulley 61 journaled under a bracket 62 on the frame, the bracket terminating in a hook 63, adapted to receive a longitudinally adjustable anchor 64. From the pulley 61, the line 42 extends beneath a vertically disposed pulley 65 carried by a bracket 66 extending outwardly from the frame. The line 42 40 passes beneath a pulley 67 on a wrist pin 68 mounted on a crank 69 carried by the shaft 15. From the pulley 67, the line 42 is trained over the pulley 7 on the mast 3.

The drives are as follows:—

45 The shaft 15 is driven from the engine 9 by the shaft 10, the pulley 11, the belt 12, and the pulley 14. Assuming that the friction wheel 18 is out of engagement with the friction wheel 17, that the friction wheel 30 is engaged with the wheel 17, and that the pinion 35 is engaged neither with the gear wheel 39 nor with the gear wheel 34, it will be obvious that, when the shaft 15 is rotated, the crank 69 and the pulley 67 will operate the line 42 in the necessary way to carry out the spudding operation.

60 The line 42 may be cast off the pulley 67, and, if the pinion 35 is engaged with the gear wheel 39, the shaft 40 will be rotated on the shaft 15, by the friction wheels 17 and 30, and by the gear elements 35 and 39, so that the line 42 will be reeled on the shaft 40.

65 It is obvious that, if desired, the friction wheel 18 may be brought into cooperation

with the friction wheel 17, thereby operating the shaft 19 to reel in or out the sand line 26.

The samson post is marked by the numeral 70, and the walking beam 71, fulcrumed on the samson post, is denoted by the numeral 71, a walking beam being connected by a pitman 72 with the crank pin 68 on the crank 69 of the shaft 15. This set up is shown in Figure 4, whereas Figure 1 shows how the parts are arranged whilst the spudding operation is being carried out.

Among other combinations, the device forming the subject matter of this application comprises a frame 1; a power shaft 15 journaled on the frame, an engine 9 on the rear end of the frame, means 12 for connecting the power shaft operatively with the engine, a friction wheel 17 on the power shaft, a sand line shaft 19 located in front of the power shaft 15, a friction wheel 18 on the sand line shaft; means 22 for mounting the sand line shaft for rotation and for swinging movement to enable the friction wheel 18 of the sand line shaft to be brought into and out of engagement with the friction wheel 17 of the power shaft, a third shaft 27 located to the rear of the power shaft 15, a friction wheel 30 on the third shaft, means 29 for mounting the third shaft for rotation and for swinging movement to enable the friction wheel 30 of the third shaft to be brought into and out of engagement with the friction wheel 17 of the power shaft, a casing line shaft 33 journaled on the frame between the third shaft and the power shaft 15, a drilling line shaft 40 journaled on the frame to the rear of the third shaft 27, gear wheels 39 and 34 on the drilling line shaft 40 and on the casing line shaft 33, a pinion 35 shiftable on the third shaft 27 into engagement with either of the gear wheels 39 and 34, means 36 for operating the shiftable pinion 35 from the forward end of the machine, and means 24—32 for moving the friction wheels 18 and 30 of the shafts 19 and 27, respectively, into and out of engagement with the friction wheel 17 on the power shaft 15.

Having thus described the invention, what is claimed is:—

1. In a device of the class described, a frame, a power shaft journaled on the frame, an engine on the rear end of the frame, means for connecting the power shaft operatively with the engine, a friction wheel on the power shaft, a sand line shaft located in front of the power shaft, a friction wheel on the sand line shaft, means for mounting the sand line shaft for rotation and for swinging movement to enable the friction wheel of the sand line shaft to be brought into and out of engagement with the friction wheel of the power shaft, a third shaft 120

located to the rear of the power shaft, a friction wheel on the third shaft, means for mounting the third shaft for rotation and for swinging movement to enable the friction wheel of the third shaft to be brought into and out of engagement with the friction wheel of the power shaft, a casing line shaft journaled on the frame between the third shaft and the power shaft, a drilling line shaft journaled on the frame to the rear of the third shaft, gear wheels on the drilling line shaft and on the casing line shaft, a pinion shiftable on the third shaft into and out of engagement with either of the gear wheels, means for operating the shiftable pinion from the forward end of the frame, and means for operating the sand line shaft and the third shaft on the forward end of the frame to bring the friction wheels on said shafts into and out of engagement with the friction wheel on the power shaft.

2. In a device of the class described, a frame, a power shaft journaled on the frame, a friction wheel on the power shaft, a sand line shaft located in front of the power shaft, a friction wheel on the sand line shaft, means for mounting the sand line shaft for rotation and for swinging movement to enable the friction wheel of the sand line shaft to be brought into and out of engagement with the friction wheel of the power shaft, a third shaft located to the rear on the power shaft, a friction wheel on the third shaft, means for mounting the third shaft for rotation and for swinging movement to enable the friction wheel on the third shaft to be brought into and out of engagement with the friction wheel of the power shaft, a casing line shaft journaled on the frame between the third shaft and the power shaft, a drilling line shaft journaled on the frame to the rear of the third shaft, gear wheels on the drilling line shaft and on the casing line shaft, and a pinion shiftable on the third shaft into engagement with either of the gear wheels.

3. In a device of the class described, a frame, a power shaft journaled on the frame, a friction wheel on the power shaft, a sand line shaft located in front of the power shaft, a friction wheel on the sand line shaft, means for mounting the sand line shaft for rotation and for swinging movement to enable the friction wheel of the sand line shaft to be brought into and out of engagement with the friction wheel of the power shaft, a third shaft located to the rear of the power shaft, gear wheels on the drilling line shaft and on the casing line shaft, and a pinion shiftable on the third shaft into engagement with either of the gear wheels.

In testimony that I claim the foregoing as my own, I have hereto affixed my signature.

MASON GILBERT CARPENTER.
